C. V. MCINTIRE

RETO RT FURNACE

Filed June 7, 1923

INVENTOR
BY Charles V. McIntire
John E. Hubbell
ATTORNEY

UNITED STATES PATENT OFFICE.

CHARLES V. MCINTIRE, OF EAST ORANGE, NEW JERSEY.

RETORT FURNACE.

Application filed June 7, 1923. Serial No. 643,5

To all whom it may concern:

Be it known that I, CHARLES V. MCINTIRE, a citizen of the United States, and resident of East Orange, in the county of Essex and State of New Jersey, have invented certain new and useful Improvements in Retort Furnaces, of which the following is a specification.

The general object of my present invention is to provide improved apparatus especially devised and adapted for use in destructive distillation and particularly in the so-called low temperature distillation of coal, at temperatures in the neighborhood of 900° F. More specifically, the object of my invention is to incorporate in, and combine with the stationary retort structure proper of my prior Patent No. 1,457,083, granted May 29, 1923, improved means for feeding the material treated through the retort and subjecting it in its passage through the retort to conditions facilitating rapid and uniform distillation at relatively low temperatures.

The various features of novelty which characterize my invention are pointed out with particularity in the claims annexed to and forming a part of this specification. For a better understanding of the invention, however, its advantages and specific objects attained with its use, reference should be had to the accompanying drawings and descriptive matter in which I have illustrated and described preferred embodiments of my invention.

Of the drawings:

Fig. 1 is a sectional elevation of the retort;

Fig. 2 is a section on the line 2—2 of Fig. 1;

Fig. 3 is a partial section on the line 3—3 of Fig. 2; and

Fig. 4 is a partial section on the line 4—4 of Fig. 2.

In the drawings, A represents a horizontally disposed stationary retort, though the axis of the retort need not be exactly horizontal. The bottom wall B of the retort A is in the form of a half cylinder corrugated to provide alternating internal and external grooves B' and B², respectively. The wall B is mounted in a refractory retort housing C, the body of which may be formed of reinforced concrete or analogous material, but the seat for the wall B, and

the walls of the off-take ports and flues are advantageously lined with fire brick, with a layer C' of infusorial earth or other refractory heat insulating material, interposed between the fire brick lining the seat for the wall B, and the concrete portion of the housing C. The wall B may advantageously be formed in arc shaped sections of suitable proportions which overlap at the joints except at the outer peripheral edges of the internal grooves B', where the joints between the adjacent section edges are sealed by contact with the refractory housing or by interposed luting material. The parts composing the wall B are preferably cast steel but they may be made of other refractory material. The ends of the external grooves B² are closed by flange portions B³ of the structure B. Suitable provisions should be made for holding the wall B in position in the retort housing with the necessary freedom for relative circular expansion and contraction of the parts lengthwise of the grooves and ribs as the temperature to which they are subjected vary. The provisions shown for this purpose comprise bell crank levers D pivotally connected to the retort housing and pressed against the flanges B³ by springs D' which are mounted in exterior spring housings.

The retort heating means comprise burners E mounted in the outer ends of burner channels F formed in the opposite sides of the retort housing and communicating with the upper ends of the arc shaped flues formed by the external grooves B² of the metallic structure B and the adjacent concave surface of the retort housing. The products of combustion escape from the flue grooves B² at their bottoms through outlet ports opening into an off-take flue C² running to a stack or other draft creating device and provided with a draft regulating damper C³. As shown the burners E are of the Bunsen type and receive fuel gas from supply mains E' through regulating valves E'.

The top wall of the retort is formed by a removable metallic cover member G covered with suitable heat insulating material G'. The ends of the retort are closed by metallic end members H and I. The coal to be carbonized, or other material treated, is fed into the retort by a screw conveyor J.

The end wall I is formed with an outlet I' for gases of distillation connected to gas piping K. A second outlet I² in the end wall I for the discharge of the semi-coke or other non-volatile residue of the material treated, opens into a discharge spout L provided with doors L' and L² which are gravity closed, and permit the discharge of the semi-coke or other residue, while preventing the outflow of gas through the opening I². In so far as above described the retort illustrated does not differ from that disclosed in my said prior Patent No. 1,457,083.

The improved means forming a part of the present invention for stirring the material treated in the retort and thereby effecting its slow gravity feed through the retort comprises an oscillating stirrer M. The stirrer M extends longitudinally through the retort and is journalled in external bearings M', suitable stuffing boxes H¹ and I¹ being provided to prevent leakage along the stirrer shaft through the end walls of the retort. Within the retort the stirrer shaft carries two sets of radial stirrer arms m and m², each of these arms being provided at its outer end with a paddle portion M² having its opposite edges inclined to correspond to the inclination of the walls of the corresponding internal groove B' which it sweeps. The arms m are longitudinally displaced, or staggered, with respect to the arms m², and the row of arms m are angularly displaced about the shaft M from the arms m², by an angle of 100° or so.

The stirrer M is oscillated back and forth through an angle of 270° or so by suitable driving connections shown as comprising a gear N secured to the stirrer shaft, and a cooperating rack bar P' connected to the piston of a hydraulic motor P. As the stirrer M is oscillated, the arms m pass between comb teeth or cleaning arms Q at the one side of the retort, and the arms m² pass between similar comb teeth or arms Q² at the other side of the retort. As shown the arms Q and Q² are anchored to the upper vertical side wall portions of the retort.

In the contemplated mode of operation of the apparatus shown in Figs. 1 to 4, in low temperature carbonization, coal is continuously fed into the retort by the conveyor J, and is worked slowly through the retort to the outlet end of the latter by the stirrer M, the semi-coke residue being discharged through the outlet I², while the distillation gases escape through the outlet I' into the pipe K which may be connected to the usual apparatus for purifying and utilizing the gas and recovering by-products therefrom. The stirrer M not only effects the desired gravity feed of the charge longitudinally of the retort, but by constantly agitating the charge, facilitates uniform and rapid distillation. The described arrangement of the

stirrer arms m and m² in two angularly displaced rows with the arms in each row staggered with respect to the arms in the other row permit each of the grooves B' to be swept by a corresponding stirrer arm, while permitting each arm to work through the material treated which would not be possible if the stirrer arms for adjacent grooves B' were side by side. The described arrangement of the arms m and m² and their oscillating movement make it possible to effectively clean the different stirrer arms and the comb cleaning teeth Q and Q² prevent the charge while in its plastic or caking condition, from collecting in unduly large masses between and around the stirrer arms m and m². Since this caking tendency ceases in an intermediate portion of the distilling operation the cleaning arms Q and Q² need extend along only a portion of the length of the retort adjacent its inlet end. The tendency toward rapid and uniform distillation resulting from the continuous and effective agitation of the material treated may be augmented, and the distillation temperature reduced and made more uniform by injecting a suitable fluid through the material treated as it passes through the retort. For this purpose I provide fluid supply pipes R with branch pipes R' which open into the retort at suitable intervals along the bottoms or outer edges of the grooves B'. The fluid injected into the retort through the pipes R' may be steam, water or a suitable gas, and in practice, I consider it preferable to thus inject into the retort a portion of the distillation gases recovered. The discharge ports at the ends of the pipes R' should be so restricted that they will not discharge too much fluid into the retort with a fluid pressure in the supply pipes R which is high enough to prevent troublesome clogging of the pipes R' by the material in the retort. The tendency of the pipes R' to become clogged is greatly minimized of course, by the fact that the stirrer arms m and m² sweep directly over the ends of the pipes R'.

While in accordance with the provisions of the statutes, I have illustrated and described the best forms of my invention now known to me, it will be apparent to those skilled in the art that changes in form may be made without departing from the spirit of my invention as set forth in the appended claims and that certain features of my invention may sometimes be used with advantage without a corresponding use of other features.

Having now described my invention, what I claim as new and desire to secure by Letters Patent, is:

1. In a horizontally disposed retort, the improvement which consists in an oscillating stirrer comprising stirrer arms arranged

- in two angularly displaced rows with the arms in each row staggered with respect to the arms in the other row, and stationary cleaning arms at opposite sides of the axis of oscillation of said stirrer arranged so that one set of stirrer arms will pass between the cleaner arms at one side of the axis while the other set of stirrer arms will pass between the cleaner arms at the other side of said axis.
2. In a retort having a bottom wall in the form of a section of a cylinder, the improvement which consists in a stirrer oscillating about an axis substantially coaxial with said bottom wall and comprising stirrer arms arranged in two angularly displaced rows with the arms in each row staggered with respect to the arms in the other row, and stationary cleaning arms at opposite sides of said axis arranged so that when said stirrer is oscillated one set of stirrer arms pass between the cleaner arm at one side of said axis, while the other set of stirrer arms pass between the cleaner arms at the other side of said axis.
3. In a horizontally disposed retort having a bottom wall in the form of a section of a circumferentially corrugated cylinder, and provided with a rotatable stirrer comprising arms the ends of which sweep along the internal corrugation grooves of said bottom when the stirrer is rotated, the improvement which consists in means comprising ports opening through said bottom wall at the outer edges of said internal grooves for injecting fluid into the retort.
4. In a retort the improvement which consists in means comprising ports in the wall of said retort for injecting fluid into the latter and a stirring mechanism in said retort for agitating the material in said retort and arranged to sweep over the inner ends of said ports.
5. In apparatus for destructive distillation comprising a horizontally disposed stationary retort, means for feeding the material to be distilled into the retort at one end, means in the retort for agitating said material to break it up and facilitate its distillation and to effect a gravity feed of the material longitudinally of the retort, the improvement which consists in means for injecting a fluid into the retort at distributed points along the bottom wall of the latter.
6. In apparatus for destructive distillation comprising a stationary retort, means in said retort for agitating the material being distilled to break it up and facilitate its distillation and means for injecting a fluid into the retort at distributed points along a portion of the retort wall normally covered by the material being distilled.

Signed at New York city, in the county of New York and State of New York this 4th day of June A. D. 1923.

CHARLES V. McINTIRE.
